Attorney

UNITED STATES PATENT OFFICE

THOMAS CHEE CHOO, OF HANNA, ALBERTA, CANADA

BRUSH

Application filed November 30, 1929. Serial No. 410,768.

The invention relates to new and useful improvements in brushes and more particularly to a fountain brush which is spontaneously supplied with the liquid or solution from an attached container in a continuous stream.

A further object is in the provision of a fountain brush of the character described having a valve for controlling the flow of liquid to the brush.

A yet further object is in the provision of a fountain brush of the character described having a pump associated with the container for to create a pressure therein to effect a pressure to the liquid or solution within the container in a manner to stimulate the discharge.

Yet another object is in the provision of a fountain-brush of the character described having a series of discharge jets arranged to discharge the liquid into the hairs of the brush and spaced at intervals across the entire width of the brush in a manner to permit even distribution of the liquid.

Other objects and many of the attendant advantages will be readily appreciated as the invention becomes better understood from a consideration of the illustrative embodiment of the same and for which purpose such descriptive drawings have been hereto appended, wherein—

Figure 1 is a perspective view of a fountain-brush embodying the rudiments of this invention, and

Figure 2 is a top plan view of the brush with parts broken away.

Referring now more in detail to the drawings in which similar reference numerals designate the corresponding parts throughout the illustration.

It will be seen that the brush is provided with a head A which is composed of two portions 6 and 7 which adjoin. The portion 6 carries the hairs 8 of the brush in its outer face and has slotted clips 9 projecting therefrom beyond its inner face 10 in a manner to embrace the adjoined portion 7. This portion 7 has a channel 12 extending crosswise thereof and produced in its inner face 11 which face meets the inner face of the ad-

joined section 6. A handle 13 is associated with portion 7 and has an elongated orifice 14 produced through the longitudinal center thereof and extending through the portion 7 to its inner face merging with the channel 12 which is disposed in transverse relation thereto. Threaded bolts 15 extend through portion 7 and are disposed near its inner face 11, being spaced to align with the slotted clips 9 of the adjoining portion 6 to engage in the slots and receive the threaded thumb screws 16 thereon to compress the clips and cause them to firmly embrace the adjoined portion. A pipe-conduit 17 having screw-caps 18^A attached to each end is embedded within the channel 12 with the caps disposed just to the exterior of the adjoined portions of the head A in a manner to be removable to permit cleaning of the conduit. This pipe-conduit has an interconnected shank-portion 18 laterally extending therefrom in a manner to extend through the orifice 14 within the handle of the brush and project slightly therebeyond, having threads 19 produced on the projecting end. A series of spouts 20 are interconnected with the pipe conduit 17 and laterally extend therefrom in an opposite direction from the shank portion 18. These spouts are spaced at equal distances throughout the length of the conduit and extend through a series of orifices produced within the adjoined portion 6, projecting just beyond the outer face of that portion, to terminate and discharge within the mass of hairs 8. A valve 21 is interconnected with the shank portion 18 and laterally extends therefrom in a manner to outstand beyond the face of the adjoined section 7. This valve is operated by a suitable handle 22 which is disposed adjacent the handles of the brush 13 to facilitate operation by the thumb of the operator in controlling the flow of liquid through the shank to the conduit and spouts.

Associated with the brush is a container 23 provided with suitable loops 24 for to receive a strap or the like therethrough for carrying purposes and also hooks 25 upon which the brushes may be hung when not in use, an opening 26 is produced in the top 100

of the container and is provided with a cap 27 for closure purposes.

Several conduits 28 depending within the container with their lower open ends lying 5 near the base and their upper open ends extending slightly above the top of the container and provided with caps 29 for closure means. A pump is associated with the container being mounted therein having its upper portion outstand beyond the wall of the container and provided with a handle 30 for operating purposes.

A hose 31 is connected by its one end to one of the conduits 28 and by its other end 15 to the projecting portion of shank 18 and interconnected brush.

In operation it will be seen that in operating this improved device, the liquid or substance to be spread is poured into the container, through opening 26 until reasonably 20 filled. Then the hose 31 and interconnected brush are attached to the extending upper end of one of the several conduits 28. Pressure is then created within the container by operating pump 32 which pressure stimulates 25 the discharge of the liquid from the container to the brush, which liquid discharges through the spouts 20 into the mass of hairs 8 as the valve 21 is operated by the operator.

It will be obvious from the foregoing description that this invention comprises important improvements in fountain brushes, and while the preferred embodiments have 30 been disclosed yet it is to be understood that minor changes in the construction and arrangement of the cooperating elements may be resorted to within the scope of what is claimed without departing from the spirit of the invention.

What I claim:—

A fountain brush comprising a head composed of separable sections, bristles mounted in one section of the head, a handle formed 45 integral with the other section of the head, a conduit extending longitudinally through said handle, a second conduit embedded in the handle section of the head and extending longitudinally thereof, at right angles to 50 said first conduit and communicating therewith, screw caps closing the ends of said second conduit, a manually controlled valve interposed in said first conduit, discharge spouts extending from said second conduit 55 at spaced intervals throughout its length, adapted to extend into the bristle section of the head when the sections are joined, bifurcated clips extending from said bristle section in overlapping relation to said handle section, and clamping bolts passing 60 through said handle section, adapted to operably engage with said bifurcated clips to secure said sections of the head together.

In testimony whereof I affix my signature.

65 THOMAS CHEE CHOO.
